J. WISNER,
Washing Machine,
No 11,737, *Patented Sept. 26, 1854.*

FIG. 1.

FIG. 3.

FIG. R.

UNITED STATES PATENT OFFICE.

JOEL WISNER, OF AURORA, NEW YORK.

WASHING-MACHINE.

Specification of Letters Patent No. 11,737, dated September 26, 1854.

To all whom it may concern:

Be it known that I, JOEL WISNER, of Aurora, in the county of Erie and State of New York, have invented a new and useful 5 Improvement in Washing-Machines; and I do hereby declare that the following is a full, clear, and exact description of the construction and operation of the same, reference being had to the annexed drawing, forming 10 part of this specification, in which—

Figure 1 is a vertical section of the machine taken through the axis of the spindle, and perpendicular to the operating lever. Fig. 2 is a plan of under surface of rubber. 15 Fig. 3 is a cross section of ribs on bottom of tub and under surface of rubber.

Similar characters of reference in the several figures denote the same part of the machine.

20 My invention which refers to the construction of the spindle upon which the rubber operates, consists in constructing the spindle in two parts; the under which passes through the rubbing disk, containing 25 a socket for the reception of the lower extremity of the upper portion of the spindle, which passes through the lever by which the rubber is operated. The arrangement, details of construction, and advantages being 30 such as will be hereafter fully set forth.

To enable others skilled in the art to make and use my invention I will proceed to describe its construction and operation.

In the drawing A is the bottom of the 35 tub, B the sides, and C the rubber. Through the bottom of the tub passes the lower portion D of the spindle, furnished with two shoulders a and b, the first being drawn against the bottom of the tub by the wedge 40 c, and the last serving as a seat for the disk B; in its top is the socket e, in which fits the conical portion of the upper spindle E. This upper spindle E passes through the bore i of the lever l, which lever is supported 45 by two standards m arising from the top of the rubber B, as partly shown by dotted lines in Fig. 1. On the inner surface of the tub bottom and lower surface of the rubber are the ribs f, each consisting 50 of semi-cylinder with a groove parallel to its axis, forming two edges n on each rib. In the rubber B are the cavities q and leading from them, the perforations r, the number depending upon the size of the disk.

55 The operation of my improved washing machine is as follows: The rubber being re-

moved from the tub, the clothes to be washed, together with a suitable quantity of water and soap are placed within the tub, as in other machines of this character. 60 The spindle E is run through the bore i of the lever l, and the bore w of the rubber B placed over the socket D; the point of the spindle E being at the same time inserted in the bore e of the socket D; the 65 disk is then allowed to descend until it rests on its seat b, and the spindle E forced down until its shoulder t rests on head of the socket D; the several parts then have the positions shown in Fig. 1 of the drawing. 70 The rubber is then partially rotated about the compound spindle D E by means of the lever l, as in other machines of this kind, the friction produced by action of the ribs and cavities removing the dirt from 75 the clothes. The edges n of the ribs giving a great increase of friction over that possessed by the ordinary cylindrical or conical ribs, while the cavities q by retaining a portion of the clothes assists in turning 80 them over and by the friction of their edges as the clothes pass from them add greatly to the effectiveness of the rubber. The perforations r permit the water to pass freely to the top of the rubber. When the 85 washing is complete the rubber is raised, the spindle E leaves the socket, and the bore of the disk passing over the socket D, the rubber is lifted out over the side of the 90 tube.

The advantages of the compound spindle D E may be simply expressed by stating, that while it steadies the rubber in its alternate partial revolutions as well as a long spindle passing through rubber and lever, 95 it obviates the necessity for lifting the bottom of the rubber to the level of the top of the long spindle, and allowing the bore of the rubber to slide over the spindle while the head is passed through the bore of the lever, which operation is both difficult and troublesome, as owing to the weight of the disk, the bore of the rubber is liable to bind before the spindle can be passed through the lever. The same inconvenience is experienced in lifting off the rubber, as after the lever leaves the spindle, the disk not being guided will fall on one side and bind the spindle. These circumstances render the lifting in and out of the rubber a very 100 troublesome operation. The difference in 105 the operation of my compound spindle is 110

apparent, as the distance which the rubber has to be lifted is but small, and the operation the same as lifting it from a short spindle passing through the rubber alone.

5 I do not claim the employment of a single spindle passing through the disk and operating lever; but

What I do claim as new and of my own invention is—

10 The compound spindle D E, composed of the socket D, and spindle E, constructed, arranged, and operating substantially as here-

in before set forth, for diminishing the amplitude of the vertical movement required in lifting in and removing the rubber, and 15 preventing the binding incident to the said operations when a single spindle is used.

In testimony wherof, I have hereunto signed my name before two subscribing witnesses.

JOEL WISNER.
